HINGE FOR SPECTACLE FRAME

Martin Obster and Anton Dietrich, Munich, Germany,
assignors to Optische Werke G. Rodenstock, Munich,
Germany

Filed Mar. 17, 1970, Ser. No. 21,934

Claims priority, application Germany Dec. 10, 1969

Term of patent 14 years

Int. Cl. D16—06

U.S. Cl. D57—1

FIG. 1.

FIG. 2.

FIG. 3.

FIG. 5.

FIG. 4.

FIG. 1 is a side elevational view of a hinge for spectacle frame embodying our new design;

FIG. 2 is a perspective view thereof;

FIG. 3 is an elevational view of the side opposite that shown in FIG. 1;

FIG. 4 is a top plan view thereof; and

FIG. 5 is a front perspective view thereof.

The spectacle frame is fragmentarily shown in broken lines for illustrative purposes only.

We claim:

The ornamental design for a hinge for spectacle frame, as shown and described.
